UNITED STATES PATENT OFFICE.

THOMAS J. REID, OF GANANOQUE, ONTARIO, CANADA.

VEHICLE-HUB.

SPECIFICATION forming part of Letters Patent No. 406,770, dated July 9, 1889.

Application filed April 17, 1889. Serial No. 307,580. (No model.)

To all whom it may concern:

Be it known that I, THOMAS J. REID, a citizen of the United States, at present residing at Gananoque, in the county of Leeds and 5 Province of Ontario, Canada, have invented a certain new and useful Improvement in Hubs for Vehicle-Wheels, of which the following is a full, clear, and exact description, reference being had to the accompanying drawings, 10 forming part of this specification.

My invention relates to improvements in shell-band hubs, in which the wooden hub is completely surrounded by a metallic shell made in two parts, the novel features of which 15 will hereinafter more fully appear.

The object of my invention is to produce a hub incased in a metallic shell, in which, when desired, cracked and checked hub-blocks may be utilized to form the core, and in which the 20 metallic shell is so arranged that the wooden hub can be tightly compressed within it, so as never to become loose by the shrinking and drying of the wooden hub when in use.

The nature of my improvements can be 25 more fully understood by a reference to the accompanying drawings, forming part of this specification.

Figure 1 is a perspective view of a checked and cracked hub-block to be used as a hub- 30 core. Fig. 2 is a side elevation of the block ready to be submitted to hydraulic pressure, and a portion of the press; Fig. 3, a perspective view of the block turned down to receive the metallic shell, and showing the key-section. Fig. 4 shows the back shell in its socket, 35 with hub in place and front shell ready to be compressed thereon. Fig. 5 is a longitudinal section of the incased hub complete and ready for the spokes. Fig. 6 is a cross-section of 40 finished hub through the center with one spoke in place. Fig. 7 shows the tenon and lower portion of the spoke before being driven.

In the drawings, A, Fig. 1, represents a cylindrical hub-block, which is to be turned 45 down to form the wooden core of the hub, as hereinafter described. This hub-block may be uncheck and perfect or checked and cracked, as shown in the drawings, and entirely worthless for a hub under old processes.

50 This cylindrical block, in order to fill up the cracks and consolidate the fibers of the wood, is placed under a hydraulic press and forced

through a tapering die C and through a circular opening D in the plate of the press E, as shown in Fig. 2. After being treated to 55 this squeezing process, which condenses the fibers of the wood, making it more solid and more pliable for the future compression, the block is then turned down, as shown in Fig. 3, to conform somewhat to the final shape of the 60 hub, although somewhat larger than the internal diameter of the metallic shell, and a groove is cut around the center to conform to the internal surface of the shell. This groove may be omitted and the shell itself made to 65 produce the groove under the subsequent pressure. The metallic shell is made in two parts. The back shell F, having cut in it the mortises for the spokes, extends considerably beyond the middle of the hub. On each side 70 and surrounding the mortises the shell is increased in thickness, so that back of the spokes an internal shoulder is formed in the shell, as at a, while the front edge of the shell is beveled upward, as at b. This back shell 75 is placed in a socket G of the same shape, and by means of hydraulic pressure the hub B is forced into place. The diameter of the hub B being somewhat more than the internal diameter of the back shell, the hub is much 80 compressed when driven into place, and is firmly locked in position by the shoulder a of the shell, the resiliency of the wood completely filling the shell and pressing strongly 85 against it. In order to prevent the shell from bursting under the pressure required when driving the hub into place, the shell may be placed within the similar-shaped socket G. In order to completely fill the shell, I also provide 90 a key or wedge-shaped piece of wood K, which is driven to place in order to expand the hub within the shell whenever this is required. The front shell L is then driven or pressed on the hub by hydraulic pressure. The internal edge of this front shell L is beveled to a somewhat sharper angle than the edge of the back shell, as shown at c, and as the front shell is 95 pressed to place this beveled edge, coming in contact with the beveled edge of the back shell, is turned down into the wood, and thus 100 the front shell is held firmly in place.

In order to lock the spokes in place, I make two or more of the faces of each mortise in the metallic shell double-beveled or rounded

outward and inward, as shown in Fig. 6. The faces of the spoke are made straight and parallel to each other, as shown in Fig. 7, and the spoke is of a size to fit within the top of the 5 mortise. The spoke is then driven to place, and, coming between the double bevels of the mortise, is first compressed and then expands to fill the lower portion of the mortise, and thus the spoke is securely locked in place.

10 Having thus fully described my invention, what I claim, and desire to secure by Letters Patent, is—

15 1. A vehicle - hub consisting of a split or checked wooden core, metallic shells for incasing said core, and a wooden wedge for expanding said core within the casing, substantially as and for the purpose set forth.

20 2. A hub for vehicle - wheels, having a wooden core made from cracked hub - blocks first compressed and subsequently expanded within a metallic shell, substantially as and for the purpose described.

25 3. In a hub for vehicle-wheels, the combination of the wooden core B and metallic shells L and F, having oppositely-beveled inner edges so inclined that the edge of one will be upset by contact with the other as the

shells are driven to place, substantially as and in the manner described.

4. In a hub for vehicle-wheels, the combination of the wooden core B and metallic shell F, extending beyond the middle of the hub, having its inner portion thickened so as to form an inwardly-projecting shoulder, substantially as and in the manner described. 35

5. In a hub for vehicle-wheels, the combination of the wooden core B, the metallic shell F, with inner portion thickened to form inwardly-projecting shoulder and inner edge beveled upward, and the metallic shell L, with 40 inner edge beveled downward, substantially as and for the purpose described.

6. As an improved article of manufacture, a hub made up of a wooden body having a single longitudinal split and a wedge-shaped 45 expanding piece tapering both longitudinally and transversely, said hub being incased by a metallic shell, within which it is expanded by the wedge-shaped piece.

THOMAS J. REID.
